UNITED STATES PATENT OFFICE.

GEORGE E. STOKES, OF BROOKLYN, NEW YORK.

DESIGN FOR A BICYCLE-STAND.

SPECIFICATION forming part of Design No. 27,273, dated June 29, 1897.

Application filed April 22, 1897. Serial No. 633,402. Term of patent 7 years.

To all whom it may concern:

Be it known that I, GEORGE E. STOKES, a citizen of the United States, residing at Brooklyn, in the county of Kings and State of New York, have invented and produced a new and original Design for Bicycle-Stands, of which the following is a specification.

The design consists in a stand for bicycles, said stand comprising side strips or bars with a flat cross-strip intermediate their ends and having at their ends eyes, and cross-pieces extended through said eyes, said cross-pieces carrying lateral arms or risers having notched tops, and cross-braces intermediate the ends of the risers, one pair of risers having connecting-arms extended to the side strips.

The design is illustrated by the accompanying drawing, in which the figure is a perspective view of the bicycle-stand.

The side strips or bars 1 have intermediate their ends a flat cross-strip 2, and at their ends the strips are provided with eyes 3. Cross-pieces 4 are extended through said eyes 3 transversely to the bars 1. Each cross-

piece carries a pair of lateral arms or risers, 25 said riser pairs being respectively shown at 5 and 6. The risers have their tops notched or forked, as at 7, and cross-braces 8 are placed intermediate the ends of the risers. One pair of risers, as 6, has connecting-arms 30 9 extended diagonally to the side strips.

By sinking or partly sinking the eyes 3 into the cross-pieces 4, as by grooving said side pieces, a finished look can be given to the device.

The design offers a striking and characteristic appearance to the eye.

What I claim as new, and desire to secure by Letters Patent, is—

The design for a bicycle-stand as herein shown and described.

In testimony whereof I have hereunto set my hand in the presence of two subscribing witnesses.

GEORGE E. STOKES.
